UNITED STATES PATENT OFFICE

CHARLES W. NEWTON, OF KANSAS CITY, MISSOURI, ASSIGNOR TO GEORGE F. NEWTON,
OF KANSAS CITY, MISSOURI

CONCRETE-FORM CLAMP AND TIGHTENER

Application filed March 12, 1928. Serial No. 261,157.

This invention relates to concrete form clamping apparatus and has for its object to produce means whereby strap iron, as distinguished from wire or rods heretofore used, 5 may be efficiently and practically applied for the clamping of concrete forms of all characters, such straps being preferable as they may be passed through cracks between the form boards without requiring the boring of 10 special holes.

Another object of the invention is to produce a clamping lug for cooperation with strap iron in the clamping of concrete forms said lug being so constructed that it shall allow 15 tightening of the strap in one direction but will hold the strap against movement in the opposite direction.

A further object of the invention is to produce an efficient tightener for cooperating 20 with strap iron, whereby the straps may be tightened.

A still further object of the invention is to produce a new and improved strap for concrete form tightening which is provided with 25 spurs to be embedded in the wood of the form, thus obviating the use of nails, and the like.

With the general objects named in view and others as will hereinafter appear, the invention consists in certain novel and useful 30 features of construction and combinations of parts as hereinafter described and claimed; and in order that it may be fully understood reference is to be had to the accompanying 35 drawing, in which:

Figure 1 is a section through a concrete floor beam form and illustrates four methods of applying the strap iron securing member of the invention.

Figure 2 is a side elevation of the structure shown in Figure 1.

Figure 3 is a top plan view of a strap member forming a part of the invention.

Figure 4 is a side elevation of the spur equipped end of said member.

Figure 5 is an end elevation of the same member.

Figure 6 is a central vertical section on an enlarged scale through a clamping lug forming 50 a part of the invention.

Figure 7 is a central vertical section through a modified form of clamping lug for securing the opposite ends of a strap encircling a suspended beam, column or the like.

Figure 8 is section of the tightener of the 55 invention.

Figure 9 is a front elevation of the tightener as shown in Figure 8.

In the said drawing, where like reference characters identify corresponding parts in 60 all of the figures, 1 indicates the clamping strap of the invention which comprises a length of strap iron of any suitable gage and length, depending upon the size of the forms to be secured, said strap at one end being 65 formed with a series of nail-receiving holes 2, and at its other end being downturned and terminating in a wood-piercing spear point 3 which may be easily driven into the wood but which will resist withdrawal on account of 70 its peculiar shape, said strap being also preferably formed near its end with a plurality of downturned V-shaped points 4 reinforced against any tendency to be straightened by 75 ribs 5, said points being cut and stamped out of the metal of the strap and leaving V-shaped openings 6 which may be used for nail-receiving openings. It will be evident 80 that if the gage of the metal is not extreme, a strap of this character may be passed through the cracks between form boards without leaving a slot large enough to cause appreciable loss of the water in the mix.

In Figure 1, four different methods of applying the straps as above outlined are 85 illustrated, as follows:

The upper strap A is indicated as having its point-equipped end bent over the edge of a longitudinally extending corbel secured to the uprights of the form, with the points driven in the vertical face of the corbel, the strap spanning the space between the forms and being nailed or otherwise fastened to the upper surface of the floor dome as illustrated.

The lower strap B is illustrated as having 90 been turned edgewise and securing the lower ends of the form uprights tightly together on top of the shores, the ends of the strap having been bent around the uprights, one 95 end having the points engaged with the wood 100

and the other end being secured by nails or the like.

The strap C has one end bent over the vertical face of a corbel as at 7, and said strap extends between the cracks in the form boards and is engaged at its other end by a tightener T (hereinafter described) which is illustrated as in the process of tightening the strap. When the form has been pulled tight, the operator or a second operator will secure the end of the strap by driving nails into the corbel by passing them through the openings 2 in the end of the strap.

The strap D is placed in a similar manner to the strap C, but is engaged at its end with a clamping lug L (hereinafter described) for holding the end of the strap as distinguished from nailing the same as with the strap C. It will be noted that in order to avoid the boring of holes or the like, a pair of two-by-fours are used, which provide an abutment for the lug and permit the strap to project without special openings.

The tightener T of the invention comprises a suitable handle 8 formed at its end with an enlarged head 9 centrally provided with a bearing for the reception of a pivot pin 10. The end of the head beyond the pivot is provided with a case-hardened toothed, transversely slideable, replaceable clamping jaw 11. The head of the handle is received between the side flanges 12 of cooperating clamping jaw 13, having its flanges pivotally mounted on the pin 10, said jaw being free to swing in one direction until stopped by a contact pin 14 carried by the handle, and in the other direction until the clamping jaws 11 and 13 come into contact.

In the use of the tool, a strap 1 is slipped between the jaws 11 and 13, and the rounded nose 16 of the jaw 13 is placed in abutment with the vertical face of a corbel or other abutment, and the operator applies force on the handle in the direction of the arrows. Figures 1 and 8. The handle swings around the pivot pin and the clamping jaw 11 carried by the handle swings into clamping engagement with the strap 1, and as the rounded nose 16 of the jaw 13 is in contact with a fixed abutment, it will be clearly apparent that the greater the strain, the tighter the tightener will clamp on the strap.

In the use of the device it has been found desirable, when there is a relatively large amount of slack to be removed from a strap, to provide a clamping lug which will efficiently catch and hold the slack as the tightener is released to take another bite. Figure 5 illustrates one method of using such a lug L and Figure 6 illustrates the lug in detail, on an enlarged scale. The lug L comprises a generally oval member in front elevation and has vertical front and back faces and is formed with a rectangular passageway 18 extending through the lug from the front to

the rear face, said passageway being of such width and breadth as to accommodate the widest and heaviest gage strap 1 with which it is devised to be employed. Extending transversely through the lug from side to side and intersecting the passageway 18, is a second passageway 19 for receiving a wedge-shaped sliding key 20 of somewhat less thickness than the width of the passageway. The key 20 is formed along its lower edge with a knife-edge 21 for cooperating with a pair of upstanding spaced lugs 22 on the bottom of the passageway 18, see Figure 6, for clamping a strap 1 to hold it against movement in the direction of the arrow. The front face of the lug is provided with a projecting lip or flange 23 to form a fulcrum for the rounded nose 16 of the tightener T, and when the combined devices are in use, it will be evident that the wedge key 20 upon a pull being applied on the strap in a direction contrary to the arrow, such pull will tend to straighten up the key and allow the strap to move, but upon release of the strain, if the strap tends to move in the reverse direction, will immediately catch as shown in the drawing and prevent such movement. When the strap has been pulled as tight as desired, the wedge key may be driven in until the strap is absolutely locked against movement.

In Figure 7, a double acting clamp 24 is illustrated for clamping the opposite ends of the strap 1 encircling an object or concrete form of any nature. The lug 24 is formed with a pair of spaced parallel strap receiving lower and upper passages 25 and 26, intersected by a slot 27 slidably receiving a double knife-edged wedge key 28 to prevent the ends of the strap from moving in the direction of the arrows. In the use of this device one end of the strap 1 is passed through slot 25 under the wedge key 28 and is bent around and under the base of the lug. This end of the strap is thus held clamped between said base and the object encircled by the strap. The other end of the strap having encircled the object, is passed through the upper slot 26. The tightener T may now be applied to said end with the round nose 16 in contact with the lug and fixed end of the strap, and the slack taken up as described in connection with Figure 9. When the strap is tight, the wedge key is hammered home to lock both ends against movement.

It is believed the construction and operation of the invention has been sufficiently set forth and that further recapitulation is unnecessary. From the above description it will be apparent that I have described and illustrated the preferred embodiment of the invention, but it is to be understood that I reserve the right to make all changes properly falling within the spirit and scope of the appended claims.

I claim:

1. A clamp lug for metallic straps having a pair of spaced passageways through the lug, and a loosely mounted transversely slideable key carried by the lug and intersecting at its opposite edges said spaced passageways.
2. A clamp lug for tie members comprising in combination with a flexible tie, of a lug secured to one end thereof, said lug having a pair of spaced passageways, the fixed end of the tie passing through one of said passageways, and a transversely slideable key carried by the lug and intersecting at its opposite edges said spaced passageways.

15 In testimony whereof I affix my signature.
CHARLES W. NEWTON.
